US0D1102275S

(12) **United States Design Patent** (10) Patent No.: **US D1,102,275 S**
(45) Date of Patent: ** Nov. 18, 2025

(54) **BOTTLE**

- (71) Applicant: **Pulpex Limited**, Sawston (GB)
(72) Inventor: **Theo Richard Ashcroft**, Sawston (GB)
(73) Assignee: **Pulpex Limited**, Sawston (GB)
(**) Term: **15 Years**
(21) Appl. No.: **29/881,154**
(22) Filed: **Dec. 28, 2022**

(30) **Foreign Application Priority Data**

(57) **CLAIM**

The ornamental design for a bottle, as shown and described.

DESCRIPTION

FIG. 1 is a top, front, right perspective view of a bottle in accordance with our new design;

FIG. 2 is a bottom, rear, left perspective view thereof;

FIG. 3 is a front view thereof;

FIG. 4 is a top view thereof;

FIG. 5 is a bottom view thereof;

FIG. 6 is a left side view thereof;

FIG. 7 is a right side view thereof; and,

FIG. 8 is a rear view thereof.

All dashed or otherwise broken lines in the figures are used for illustrative purposes only to give environmental context and form no part of claimed design.

1 Claim, 4 Drawing Sheets
